PIVOTED ANGULAR BENDER

Benjamin A. Woina, Salem, Ohio, assignor to
 Mullins Manufacturing Corporation, Salem,
 Ohio, a corporation of New York

Application June 10, 1946, Serial No. 675,659

3 Claims. (Cl. 153—12)

1

This invention relates to a sheet metal forming apparatus and more particularly to a device for forming sharp cornered bends. In the construction of metal cabinets, furniture and similar articles, the formation of sharp corners, usually right-angle corners, has heretofore been performed by die pressing or in a sheet metal brake. Where a flat or formed sheet metal piece is to be given one or more right-angled or other sharp cornered bends, these methods are sometimes cumbersome or difficult to apply.

It is an object of the present invention to provide an improved bending apparatus in which a sharp cornered bend may be readily formed in a strip or sheet of metal, for example, one having upturned flanges such as a channel member.

A further object is to provide a device of this character wherein a forming head of simple and compact construction may be utilized and which is so arranged that a plurality of such heads may be located at different corners of a die block around which a sheet is to be formed with several sharp cornered bends.

Figure 1 is a plan view of a metal bending apparatus incorporating a preferred form of the present invention.

Figure 2 is a perspective view of a typical work piece after forming.

Figure 3 is a view corresponding to Figure 1 showing the parts in a different position.

Figure 4 is a plan view of a metal bending fixture incorporating several of the forming heads illustrated in Figures 1 and 3.

Figure 5 is a partial section on line 5—5 of Figure 1.

Figure 6 is a partial section on line 6—6 of Figure 1.

Figure 7 is a view taken on line 7—7 of Figure 1.

Figure 8 is a view taken on line 8—8 of Figure 1.

Figure 9 is a sectional view on line 9—9 of Figure 3.

Referring now to Figure 2, there is shown a typical work piece which the device of the present invention is particularly adapted to form. Thus, a sheet metal channel 10 having upturned flanges 12 on either side may have its flanges notched out in the well-known manner at 14 where corners are to be formed and the flat web of the channel is then bent to the shape illustrated in Figure 2. Such a piece is commonly used as a support for sheet metal base cabinets.

The preferred form of the forming device illustrated comprises a main forming head member

2

16 which may be secured to a piston rod 18 forming part of a conventional fluid operating cylinder. The head 16 may be guided on stationary ways 20. Rigidly associated with the ways 20 is a stationary die block 22 having one or more right-angled sharp corners 24, 26 and 28 about which the work piece is to be formed. The main head 16 has secured thereto or formed integrally therewith a cam member 30 having an inclined and curved cam face 32 for a purpose later to be described. Slidably and yieldably associated with the forming head 16 is a hold-down plate 34. The latter may be guided on suitable dowels 36 and bushings 38 secured to the forming head 16. Suitable headed retainers 40 also secured to the head 16 limit the separation between head 16 and hold-down block 34. Positioned in recesses 42 are a plurality of compression springs 44 which normally urge the hold-down block 34 at its maximum extension from the head 16 as shown in Figure 3. The hold-down block may have flanged portions 46 adapted to overlie the flanges 12 of the work piece 10 as shown more clearly in Figure 5. Pivoted on studs 48 in the flanges 46 is a rocker plate 50 (see Figure 6) which may also have upturned flanges 52 on its right-hand face in Figure 3 and flanges 54 on its left-hand face in Figure 3. The latter are adapted to overlie the flanges of the work piece while the former are contacted by the cam face 32 and provide clearance for a spring 56 which normally retains the rocker plate in the position illustrated in Figure 3. In Figure 9 the flanges 52 and 54 are shown in cross-section. The pivot studs 48 are accurately positioned so that the pivoting axis will lie substantially on the corner 24 except that it is spaced upwardly and rightwardly therefrom, in Figure 1, by the thickness of the sheet metal work piece.

In operation, considering the action of a single forming head as illustrated in Figures 1 and 3, the head when projected to the left from the position shown in Figure 3 will bring the hold-down block 34 into contact with a work piece 10 which is positioned upon the stationary die block 22; a portion of the work piece overhanging upwardly above the corner 24. Thereafter further movement of the forming head 16 driven by the piston rod 18 will compress the springs 44. At the same time, the cam block 30 will contact the rocker plate 50 along the flanges 54 swinging it counter-clockwise to the position illustrated in Figure 1. This carries the overhanging end of the work piece with it and wraps the same snugly around the corner 24 of the die block 22. The flanges 52

of the rocker plate as well as the flanges 46 of the hold-down block serve to retain the flanges 12 of the work piece during this operation. The cam block 30 is shaped to contact rocker plate 50 at its outer end where the most leverage is obtained for the initial movement. The contact moves inward to full contact and still further toward the pivot point 48 as movement progresses. At the same time, the hold-down block firmly grips the work piece and clamps it to prevent displacement thereof during the bending operation.

Upon retraction of the piston rod 18 and head 16, the cam block 30 will permit spring 56 to restore rocker plate 50 to its former position and after a predetermined retraction will pick up the hold-down block 34 returning it to the position illustrated in Figure 3.

As seen more particularly in Figure 4, a plurality of similar forming heads together with their guide ways and actuating cylinders may be mounted at the various corners of the die block 22. Thus a straight flanged work piece may be progressively bent first at one corner and then at the next proceeding counterclockwise around the die block. For this purpose, suitable automatic sequence controls for the actuating cylinders well-known in the art may be provided.

It will thus be seen that the present invention has provided a simple rugged forming tool which is compact and self-contained. Likewise, it is particularly adapted to the construction of special bending machines for forming one particular size part to a given contour in that the forming heads are inexpensive and may be used over again in other setups when the usefulness of a given setup has ended. The heads are also well adapted for use with simple fixtures in a press of conventional construction, in which case, a single die block may be mounted rotatably on an axis perpendicular to the press ram movement and indexed progressively to properly position the corners thereof sequentially under a single forming head.

I claim:

1. A sheet metal forming device comprising a die block having two angularly related flat surfaces meeting in a sharp external corner, and a forming head, said die block and head being mounted for movement of one relative to the other perpendicularly to one of the flat surfaces, a hold-down block yieldably carried by the forming head to clamp a work piece against said one surface with a portion overhanging the corner, a rocker plate pivoted to the hold-down block on an axis coincident with the outside corner of the work piece when formed, and a cam block rigidly secured to the forming head for pivoting the rocker plate and the overhanging part of the work piece around the corner of the die block.

2. A sheet metal forming device comprising a die block having two angularly related surfaces meeting in a sharp external corner, and a forming head comprising a hold-down block yieldably

carried by the forming head to clamp a work piece against one surface with a portion overhanging the corner, said die block and head being mounted for movement of one relative to the other perpendicularly to one of the surfaces, a rocker plate pivoted to the hold-down block on an axis coincident with the outside corner of the work piece when formed, and a cam block rigidly secured to the forming head for pivoting the rocker plate and the overhanging part of the work piece around the corner of the die block as the forming head moves toward the die block, the cam block having an angular surface projecting forward to contact the rocker plate initially at a point remote from the axis of pivot and arranged to bear entirely on the plate during one point of travel and to shift the pressure point inward toward the axis as the movement progresses.

3. A sheet metal forming device comprising a die block having two angularly related surfaces meeting in a sharp external corner, and a forming head comprising a hold-down block yieldably carried by the forming head to clamp a work piece against one surface with a portion overhanging the corner, said die block and head being mounted for movement of one relative to the other perpendicularly to one of the surfaces, a rocker plate pivoted to the hold-down block on an axis coincident with the outside corner of the work piece when formed, and a cam block rigidly secured to the forming head for pivoting the rocker plate and the overhanging part of the work piece around the corner of the die block as the forming head moves toward the die block, the cam block having an angular surface projecting forward to contact the rocker plate initially at a point remote from the axis of pivot and arranged to bear entirely on the plate during one point of travel and to shift the pressure point inward toward the axis as the movement progresses, the rocker plate having a pair of flanges on opposed sides, one pair being positioned to overlie the work piece at the die block and the other pair being positioned to contact the cam block, and a return spring fastened at one end to the hold-down block and at the other end to the rocker plate in the recess between the last named pair of flanges to return the rocker plate to initial position.
